UNITED STATES PATENT OFFICE.

MYER ROBERTS, OF PHILADELPHIA, PENNSYLVANIA.

COAT POCKET.

Application filed July 13, 1922. Serial No. 574,636.

To all whom it may concern:

Be it known that I, MYER ROBERTS, a citizen of the United States, residing at Philadelphia, in the county of Philadelphia and 5 State of Pennsylvania, have invented certain new and useful Improvements in Coat Pockets, of which the following is a specification.

My invention relates to apparel and more 10 particularly to pockets for coats and jackets.

The object of the invention is to provide an improved pocket construction by which 15 pockets of various styles may be provided with a number of pocket compartments, including a plurality of large or main compartments and a small or cash compartment in each of the large compartments, thus increasing the pocket space and capacity, and providing an element of safety 20 against loss or pocket picking.

These objects, and other advantageous ends which will be described hereinafter, 25 I attain in the following manner, reference being had to the accompanying drawings in which—

Figure 1 is a face view of a portion of a coat or other garment equipped with one 30 form of pocket, designed as a combination flap and uncovered pocket.

Figure 2 is a view similar to Figure 1 with the flap turned into the outer compartment,

Figure 3 is an enlarged sectional view 35 taken on the line 3—3 of Figure 2,

Figure 4 is an enlarged vertical sectional view taken on the line 4—4 of Figure 2,

Figures 5 and 6 are views similar to Figures 1 and 2 showing the invention applied 40 to a patch pocket,

Figures 7 and 8 are enlarged sections similar to Figures 3 and 4, taken on the lines 7—7 and 8—8 of Figure 6,

Figures 9 and 10 are also views similar 45 to Figures 1 and 2, of another form of pocket, and

Figures 11 and 12 are sectional views taken on the lines 11—11 and 12—12 of Figure 10.

50 Referring to Figures 1 to 4 of the drawings, 1 designates outside material or cloth of a garment, such as a coat, in which is provided a slit 2 to form an entrance opening for a pocket. The pocket has an inner compartment 3 and an outer compartment 4. These compartments are

formed between inner, intermediate and outer plies 5, 6 and 7 of lining cloth of which pocket linings are usually made. At slit 2 the outside material 1 is cut away so 60 that the lower part is vertically spaced from the upper part.

The upper edge of ply 5 is sewed to the top edge of the outside material at slit 2 as indicated at 8, top edge of ply 7 is sewed 65 to the bottom edge of the outside material at slit 2, as indicated at 9, preferably with a reinforcement and welt 10, and the side and bottom edges of plies 5, 6 and 7 are sewed together as indicated at 11.

The top edge of ply 7 is lower than top 70 edges of plies 5 and 6, thus exposing upper portion of ply 6, which is reinforced as indicated at 12. A folded upper edge 13 of a flap 14 is secured to this reinforced 75 upper edge of ply 6 and projects above said edge to overlie the outside material above slit 2.

The flap 14 is free of the outside material 80 at slit 2 but is sewed across the pocket by two spaced rows of stitching 15 and 16 adjacent the upper edge 13 and spaced below the same adjacent the bottom edge of the outside material at slit 2 and welt 10. The 85 ends of flap 14, between the rows of stitching 15 and 16, are also sewed to the outside material as indicated at 17 and compartment 4 is slightly wider than flap 14 so that the latter may be left out, as in Figure 1, to give the appearance of a concealed 90 and covered pocket, or turned in, as in Figures 2 and 4, to give the appearance of an uncovered or semi-patch pocket.

A section 18 of material corresponding 95 to the material of ply 5 is sewed to the ply 5 near the top of compartment 3, thus providing a small or cash pocket or compartment 19 accessible through the entrance opening of compartment 3. A section 20, 100 of material corresponding to ply 6, is secured to the ply 6 at a point below the compartment 19, to provide a small or cash pocket or compartment 21 which is accessible through the entrance opening of compartment 4. When flap 14 is turned in as 105 shown in Figures 2 and 4 of the drawings, the compartment 21 is covered thereby. This, in conjunction with the fact that there are two entrance openings and the structure is such that the manner of entrance into the pocket is puzzling to any 110 one not familiar with its structure, pro-

vides an element of safety against loss or pocket picking.

In the form shown in Figures 5 to 8 of the drawings, the outside material is designated at 22 and a section 23 of such material is sewed to the outside material of the garment at the sides and bottom edge, as indicated at 24, to provide a patch pocket. The top of section 23 is left free of the outside material to provide an entrance opening for a compartment 25 formed between the material 22 and a ply 26 sewed in position to correspond with section 23. Section 23 is provided at the top with a strip 27 which is folded inwardly and downwardly for connection to the upper edge of ply 26 as indicated at 28 and a reinforced flap 29 is secured beneath the folded portions as indicated at 30. Section 23 is reinforced as indicated at 31, provided with a welt 32 at the top edge, and co-operates with ply 26 to form a compartment 33 of a width greater than flap 29 so that the latter may be turned in from the position shown in Figure 5 to position shown in Figures 6 and 8. By this means a patch pocket, with or without a flap, is provided, and when the flap is turned out as in Figure 5, compartment 33 will be covered. A section 34 is secured to material 22 in compartment 25 to form a small or cash pocket 35 and a similar section 36 is secured to ply 26 within compartment 33 to form a cash pocket 37 which is covered when flap 29 is turned in.

In Figures 9 to 12 of the drawings, the construction is practically the same as that described in connection with Figures 5 to 8 inclusive except that in lieu of the flap 29, a flap 38 is sewed or otherwise anchored directly to the outside material above the compartment 25, as indicated at 39. A strip 40 corresponding to strip 27, is provided with a welt 41 and the entrance opening to the outer compartment 33 is between the welts 32 and 41. Strip 40 is attached to the reinforced upper edge of a ply 42 so that in this form, as in the forms previously described, the entrance openings of the large compartments are located one below the other. In this form, flap 38 may be arranged to cover the entrance openings as shown in Figure 9, but is wider than the entrance openings so that the flap must be raised, as shown in Figures 10 and 12, in order to obtain access to any of the compartments.

While I have described my invention as

taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. The combination with a garment having a pocket opening of plies of cloth sewed to the garment around the opening to form two compartments, the outer ply being sewed to the edge of the opening; a welt interposed between the edge of said ply and the edge of said opening and sewed thereto; a section of cloth sewed to the ply which forms the inner side of the outer compartment to provide a pocket; a flap sewed to the upper edge of said ply and extending below the upper edge of the pocket, and a section of cloth sewed to the inner side of the inner compartment to provide a pocket having its entrance opening above the entrance opening of the first pocket and its bottom above the bottom of the first pocket.

2. The combination with a garment having a pocket opening of plies of cloth sewed to the garment around the opening to form two compartments, the inner ply being sewed to the upper edge of the opening, the outer ply being sewed to the lower edge of the opening, the intermediate ply having its upper edge folded downwardly; a welt interposed between the edge of the outer ply and the lower edge of the opening and sewed thereto; a flap sewed to the folded edge of the intermediate ply and extending downwardly; a section of cloth sewed to the ply to provide a pocket having its entrance opening above the lower edges of the downwardly extending fold and flap, and a section of cloth sewed to the inner ply to provide a pocket having its entrance opening above the entrance opening of the first pocket and its bottom above the bottom of the first pocket.

In testimony whereof I have signed my name to this specification in the presence of two subscribing witnesses.

MYER ROBERTS.
